UNITED STATES PATENT OFFICE.

CHARLES A. ROBBINS, OF NEVADA, AND JASPER W. JOLLEY, OF MORRAL, OHIO.

FIRE-POT FOR STOVES AND FURNACES.

1,238,942.

Specification of Letters Patent. Patented Sept. 4, 1917.

Application filed November 25, 1916. Serial No. 133,363.

To all whom it may concern:

Be it known that we, (1) CHARLES A. ROBBINS and (2) JASPER W. JOLLEY, citizens of the United States, residing at (1) Nevada, 5 (2) Morral, in the county of (1) Wyandot, (2) Marion, and State of (1) Ohio, (2) Ohio, have invented certain new and useful Improvements in Fire-Pots for Stoves and Furnaces; and we do hereby declare the following to be a full, clear, and exact description of the invention, such as will enable others skilled in the art to which it appertains to make and use the same.

The invention relates to improvements in 15 fire pots for stoves and furnaces.

The object of the present invention is to improve the construction of fire pots for stoves and furnaces and to provide a simple, practical and comparatively inexpensive fire 20 pot designed to be constructed in various sizes for different kinds of stoves and furnaces and equipped with a hollow section capable of adjustment to arrange it at different portions of the fire pot whereby the 25 hollow water receiving section may be placed in the most advantageous position to secure the maximum heating effect.

A further object of the invention is to provide a fire pot of this character equipped 30 with an adjustable water receiving portion or hollow section adapted to be arranged at either the top or bottom of the fire pot to adapt it for overfed or underfed stoves and furnaces.

With these and other objects in view, the 35 invention consists in the construction and novel combination of parts hereinafter fully described, illustrated in the accompanying drawing, and pointed out in the claims here- 40 to appended; it being understood that various changes in the form, proportion, size and minor details of construction, within the scope of the claims, may be resorted to without departing from the spirit or sacrificing 45 any of the advantages of the invention.

In the drawing—

Figure 1 is a perspective view of a fire pot constructed in accordance with this invention and shown applied to a portion of a 50 furnace,

Fig. 2 is a plan view of the same,

Fig. 3 is a vertical sectional view of the fire pot, the hollow water receiving section being arranged at the bottom thereof,

55 Fig. 4 is a similar view showing the hol-

low water receiving section arranged at the top of the fire pot.

Like numerals of reference designate corresponding parts in the several figures of 60 the drawings.

In the accompanying drawing in which is illustrated the preferred embodiment of the invention, the fire pot comprises in its construction a solid section 1 and a hollow section 2 adapted to receive water and capable 65 of being arranged either below the solid section 1 as illustrated in Figs. 1 and 3 of the drawing, or upon the solid section 1 as shown in Fig. 4 to adapt the fire pot for overfed and underfed stoves and furnaces. The sections are of the same size and shape and 70 they are tapered and each is provided at the upper edge with an annular groove 3 and at the lower edge with a depending flange 4, the flange of each section being adapted 75 to fit in the groove or seat 3 at the top of the other section whereby the two sections are reversible or interchangeable. By this construction, the hollow section which receives the water is adapted to be arranged in 80 the most advantageous position for obtaining the maximum heating effect of a fire whether the same be overfed or underfed.

The form of the fire pot sections may be 85 varied and the size will be in accordance with the stove or furnace to which the fire pot is designed to be applied. The hollow section is tapped at the inner side at the upper portion to receive elbows 5 or any 90 other suitable pipe connections and the elbows 5 are connected by suitable pipes 6 with a manifold 7 which is located within the stove or furnace at the interior of the fire pot as shown in Fig. 3 or at a point adjacent 95 to the fire pot as illustrated in Fig. 4 in order to subject the manifold to the intense heat adjacent to the fire. The manifold is connected with a supply pipe or water flow pipe 8 which is designed to extend to the radiators and the said hollow section is 100 tapped exteriorly for one or more return pipes. In Fig. 4 of the drawing the hollow section is shown arranged upon the solid section and by reversing the section, the water section may be arranged either upon the 105 grate or at the upper portion of the fire pot. By this construction and operation the hollow or water section may be arranged at the point where it will be heated to a maximum degree by the fire.

What is claimed is:—

1. A fire pot composed of two correspondingly shaped sections, one of the sections being solid and the other being hollow and having inlet and outlet apertures, said sections being provided at their upper and lower edges with interlocking means whereby either of the said sections may be arranged upon the other to locate the hollow section at the upper or lower portion of the fire pot.
2. A fire pot of the class described comprising two correspondingly shaped reversible sections, one of the sections being solid and the other section being hollow and having inlet and outlet apertures for the circulation of water, said sections being provided at their upper and lower edges with coacting interlocking means of uniform diameter whereby the upper or lower edge of either section may be interlocked with the other section to arrange the hollow section at the upper or lower portion of the fire pot.
3. A fire pot of the class described comprising two correspondingly shaped reversible sections, one of the sections being solid and the other section being hollow and having inlet and outlet apertures for the circulation of water, said sections having meeting upper and

lower edges whereby either section may be 30 arranged upon the other to locate the hollow section at the upper or lower portion of the fire pot.

4. A fire pot of the class described comprising two correspondingly shaped reversible sections, one of the sections being solid and the other section being hollow and having inlet and outlet apertures for the circulation of water, said sections having meeting upper and lower edges whereby either section 35 may be arranged upon the other to locate the hollow section at the upper or lower portion of the fire pot, pipes connected with the hollow section at the upper portion of the inner side thereof, a manifold receiving 40 the said pipes and located at the top of the hollow section so as to be subjected to the intense heat of the fire, and a return pipe connection with the hollow section at the lower portion of the exterior of the same. 45

In testimony whereof we affix our signatures in presence of two witnesses.

CHARLES A. ROBBINS.
JASPER W. JOLLEY.
